UNITED STATES PATENT OFFICE

163,048

NEEDLE THREADER

Julian Seth Kahn, Brooklyn, N. Y.

Application December 12, 1950, Serial No. 13,394

Term of patent 14 years

(Cl. D3—19)

To all whom it may concern:

Be it known that I, Julian Seth Kahn, a citizen of the United States, residing at Brooklyn, in the county of Kings and State of New York, have invented a new, original, and ornamental Design for a Needle Threader, of which the following is a specification, reference being had to the accompanying drawing, forming part thereof.

Fig. 1 is a perspective view of a needle threader, showing my new design.

Fig. 2 is a side elevational view of the needle threader shown in Fig. 1.

Fig. 3 is a top plan view thereof.

Fig. 4 is a bottom plan view thereof.

Fig. 5 is an end view thereof, as seen from the left of Fig. 2.

Fig. 6 is an end view thereof, as seen from the right of Fig. 2.

Fig. 7 is a view similar to Fig. 2, but showing the operating handle withdrawn.

I claim:

The ornamental design for a needle threader, substantially as shown.

JULIAN SETH KAHN.
